UNITED STATES PATENT OFFICE.

ROBERT S. KNODE, OF FORT WAYNE, INDIANA, ASSIGNOR OF ONE-HALF TO
EMMETT L. SIVER, OF SAME PLACE.

ATOMIZER.

SPECIFICATION forming part of Letters Patent No. 399,539, dated March 12, 1889.

Application filed October 4, 1888. Serial No. 287,339. (No model.)

To all whom it may concern:

Be it known that I, ROBERT S. KNODE, a citizen of the United States, residing at Fort Wayne, in the county of Allen, in the State of Indiana, have invented certain new and useful Improvements in Atomizers; and I do hereby declare that the following is a full, clear, and exact description of the invention, which will enable others skilled in the art to which it applies to make and use the same, reference being had to the accompanying drawings, which form part of this specification.

My invention relates to improvements in atomizers or apparatus for spraying for use principally in the treatment of nasal, ear, and throat diseases; and the object of my improvements is to provide an instrument which can easily be made to eject spray from the nozzle in any direction required by the operator, thus avoiding the use of different instruments or the necessity of withdrawing the instrument to change the nozzle. I attain these objects by the use of the mechanism illustrated in the accompanying drawings, in which—

Figure 1 shows a side elevation of one form of apparatus illustrating one feature of my improvements. Fig. 2 is a side elevation of an apparatus illustrating a preferable construction. Fig. 3 is a side elevation of apparatus when used with a bottle or other receptacle not attached to the separable connecting-tube. Fig. 1' is an end view of Fig. 1. Fig. 2' is an end view of Fig. 2, section being made on the line x' y' . Fig. 2'' is an end view of Fig. 2 from the other direction; and Fig. 3' is an end view of Fig. 3 as seen from the left-hand end.

Similar letters refer to similar parts.

The tube A is the common air-tube used in all spraying apparatus. The tube B is the liquid-tube, which conveys the fluid to the nozzle a of the air-tube, the two being suitably fastened to each other. This liquid-tube B has heretofore been connected directly to the cup C or other vessel containing the supply of fluid to be used.

In my improvements I make a separate connection by constructing on this supply-tube B a sleeve or collar, c , having an open orifice at the end d ; or the tube B may be made

a connecting-tube, D, sufficiently tight to prevent leakage, while permitting the tube A, with its connections, to be rotated upon it. The other end of the connecting-tube D is attached to the cup C, which contains the liquid to be sprayed. The attachment to the liquid-receptacle may be made permanently, as in Fig. 2, or removably, as in Fig. 3. This attachment may be permanent, as shown in Figs. 1 and 2; or the end f may be lengthened, as shown in Fig. 3, and inserted in any suitable vessel, E, containing liquid to be used. This connecting-tube may be made straight between the tube B and the cup C, as shown in Fig. 1, in which case the air-tube A is bent in the form shown, so as to permit the rotation of the air-tube A around the tube D, while the cup C is held in an upright position; but a preferable mode of construction, involving another feature of my improvements, is shown in Fig. 2. The connecting-tube D is constructed with two curves, one at right angles, the part inserted in the sleeve c , and the other a side curve, as shown in Figs. 2', 2'', and 3'. The purpose of this construction of a side curve is to permit the cup C or other liquid-containing vessel to be held upright, so as not to spill its contents when the tube A, with its connections, is rotated so far around the tube D as to throw the nozzle a of the air-tube A straight down, coinciding with the line of gravity. The side curve then permits the tube A to be directly over the tube B, as shown in Figs. 2, 2', and 2''.

Where it is desired to use fluids from a bottle or other receptacle, the connecting-tube D, constructed with two curves, as described, with its end f suitably lengthened, as shown in Fig. 3, is used separately for that purpose, the end e being inserted in the sleeve c or pipe B and the end f passed into the bottle or other vessel.

The operation is as follows: The cup C or other vessel containing the liquid to be sprayed and the connecting-tube D are held in one hand, the cup or vessel in an upright position, and the nozzle is inserted in the throat of the patient or any other place required. The operator with the other hand then turns the nozzle in the direction he desires to throw the

spray by rotating the tubes A and B around the connecting-tube D as an axle. The air is then forced through the air-tube A, ejecting the spray in the usual manner.

5 Having thus described my invention, what I claim as new, and desire to secure by Letters Patent, is—

1. In an atomizing apparatus, the combination of the air-tube A with the liquid-tube B, with the sleeve c, the connecting-tube D, and the cup C, for the purpose and substantially as described.

2. In an atomizing apparatus, the combination of the separable connecting-tube D, constructed with two curves, with a liquid-tube 15 adapted to be rotated thereon, and with a vessel for containing the liquid to be sprayed.

In testimony whereof I do hereto subscribe my name, in the presence of two witnesses, this 24th day of September, A. D. 1888.

ROBERT S. KNODE.

Witnesses:
